BY *John B. Brady* ATTORNEY.

ATTORNEY

UNITED STATES PATENT OFFICE.

FREEMAN H. OWENS, OF NEW YORK, N. Y.

SPRING LOCK FOR INCANDESCENT LAMPS.

Application filed March 17, 1926. Serial No. 95,304.

My invention relates broadly to incandescent lamps and more particularly to a spring lock for preventing the loosening and extinguishing of lamps by vibration.

5 One of the objects of my invention is to provide a construction of spring lock for preventing the loosening and extinguishing of incandescent lamps under conditions of vibration, which may be readily manufactured inexpensively on a quantity production basis.

Another object of my invention is to provide a spring lock device which may be readily applied to incandescent lamps and sockets of standard construction with only slight modification, making it unnecessary to increase the cost of the lamp or socket construction to any substantial degree.

My invention will be more clearly understood from the specification hereinafter following by reference to the accompanying drawings in which Figure 1 shows an incandescent lamp and socket mounting therefor with the lamp removed from the socket 20 and showing the application of the spring lock of my invention; Fig. 2 illustrates an incandescent lamp which has been screwed into the lamp socket and locked against accidental unscrewing by virtue of the locking device of my invention; Fig. 3 is a cross-sectional view taken on line 3-3 of Fig. 1 through the base of an incandescent lamp constructed in accordance with my invention; Fig. 4 is a cross-sectional view taken 25 through the base of the incandescent lamp in locked position within the lamp socket on line 4-4 of Fig. 2; and Fig. 5 is a perspective view of the spring lock arrangement which cooperates with indentations in the screw threads on the base of a lamp for preventing the unscrewing of the lamp from the base under conditions of vibration.

I am familiar with various constructions of locking devices for preventing theft of 45 incandescent lamps from the lamp socket. Generally a key locking device is provided which is both complicated and relatively expensive in construction.

The purpose of the device of my invention 50 is to provide a simplified construction of spring lock which prevents the incandescent lamp from turning to such a degree that the lamp may become extinguished under conditions of mechanical vibration while freely permitting the removal and replacement of

a lamp in the socket. I provide a plurality of indentations along the screw threads on the base of the lamp with a cooperating spring device carried by the lamp socket which resiliently interlocks with the indentations in the base of the lamp for preventing the turning of the lamp in its socket under conditions of vibration.

Referring to the drawings in more detail reference character 1 designates a socket shell for an incandescent lamp with an inferiorly screw threaded shell therein to receive the base 5 of an incandescent lamp 4. The screw threaded shell 2 is apertured at 3 with the aperture extending over a width 60 substantially larger than the width of one thread 6 on the base of the lamp 5. The base 5 of the incandescent lamp 4 is provided with parallel extending rows of indentations 7, 8, 9, 10 and 11 formed in the screw thread 6 of the base 5. Around the outside of the shell 2 I provide a resilient wire device, shown more clearly in Fig. 5, having circular portions 12 integrally related to a substantially U shaped head 13 which extends 65 through the aperture 3 in the shell 2 and terminating in ends 14. The wire like member 12, 13 and 14 is substantially a spring coil which tends to grip the outside of the shell 2 and exert an inward pressure through 70 aperture 3. The resilient locking head 13 engages the detents 7, 8, 9, 10 and 11 as the lamp is screwed into its socket and tends to prevent rotation of the lamp in the socket 75 under conditions of vibration. The resilient head 13, however, is readily moved outwardly and the detents disengaged therefrom when applying a positive rotative force of relatively large magnitude to the lamp 80 when it is to be manually removed from the 85 socket for replacement.

My invention finds particular application in incandescent lamp lighting installations on shipboard, railroad trains and in other instances where the lighting installation is 90 subject to continuous shock vibration. I have found in many instances that lamps in the usual form of incandescent lamp sockets unscrew of their own accord under conditions of continuous vibration, with the result that the lamp is extinguished. The construction of spring locking device of my invention is such that it may be readily manufactured inexpensively on a quantity production basis. The resilient wire device 105 110

- snugly conforms with the contour of the screw threads on the outside of the lamp socket enabling standard parts to be used with substantially no modifications. The resilient wire member is given a pitch substantially equal to the pitch of the screw threads on the exterior of the socket so that the member may be screwed into place on the outside of the socket.
- 10 While I have described my invention in a certain particular embodiment I desire that it be understood that modifications may be made and that I intend no limitations upon my invention other than are imposed by the scope of the appended claims.

What I claim as new and desire to secure by Letters Patent of the United States is as follows:

1. A spring locking device for incandescent lamps having a threaded base adapted to engage a screw threaded socket, said locking device including a plurality of rows of indentations formed in the screw threaded base of said lamp and a spring wire member having portions bent upon themselves forming a pair of parallel extending portions encircling said screw threaded socket and passing through an aperture therein for engaging the indentations formed in said screw threaded base for preventing said base from turning in said socket under conditions of shock vibration.
2. A spring locking device for incandescent lamps having a screw threaded base for engaging a screw threaded socket comprising a spring wire member doubled upon itself and encircling said socket and passing through an aperture in one side thereof, a plurality of indentations formed on the screw threaded base of said lamp, said spring device operated to engage said indentations through said aperture for preventing the unscrewing of said base under conditions of shock vibration.
3. A locking device for incandescent lamps having a screw threaded base adapted to engage a screw threaded socket, said locking device including a plurality of indentations formed in said screw threaded base and a spring wire member having a pair of parallel extending portions encircling said screw threaded socket and extending through one wall thereof for engaging the indentations formed in said screw threaded base when said incandescent lamp is screwed into

said socket for preventing the unscrewing of said lamp under conditions of shock vibration.

4. A locking device for incandescent lamps comprising in combination with a screw threaded socket an incandescent lamp having a screw threaded base adapted to engage said socket, a plurality of indentations formed in said screw threaded base, a wire like member doubled upon itself and encircling the screw threads on said screw threaded socket and passing through one wall thereof for engaging the indentations on said screw threaded base when said incandescent lamp is screwed into said socket for preventing the unscrewing of said incandescent lamp from the socket under conditions of shock vibration.

5. A locking device for incandescent lamps comprising in combination with a screw threaded socket an incandescent lamp having a screw threaded base adapted to engage said socket, a plurality of indentations formed in said screw threaded base, a wire like member bent upon itself and having a pitch substantially equal to the pitch of the screw threads on said socket, said wire member having a substantially square nose portion and a pair of parallel extending portions connecting said nose portion and embracing the exterior screw threads of said socket and extending through one wall thereof for engaging the indentations on said base when said incandescent lamp is screwed into said socket, whereby said lamp is prevented from unscrewing from said socket under conditions of shock vibration.

6. A locking device for incandescent lamps having a screw threaded socket arranged to receive an incandescent lamp having a screw threaded base, a plurality of indentations formed in said screw threaded base, a wire member bent into substantially a U shaped form and arranged to encircle the exterior of the screw threads of said socket with the U shaped head of said wire member passing through one wall of said socket for engaging the indentations formed in the base of said lamp when the said lamp is screwed into said socket, whereby said lamp is prevented from unscrewing from said socket under conditions of shock vibration.

In testimony whereof I affix my signature.

FREEMAN H. OWENS.
